UNITED STATES PATENT OFFICE.

JACOB B. BERLAND, OF ST. LOUIS, MISSOURI.

DESIGN FOR A STORE FRONT.

Application filed December 9, 1927. Serial No. 24,423. Term of patent 14 years.

To all whom it may concern:

Be it known that I, JACOB B. BERLAND, a citizen of the United States, residing in the city of St. Louis, State of Missouri, have invented a certain new, original, and ornamental Design for Store Front, of which the following is a specification, reference being had to the accompanying drawing forming a part thereof.

The drawing illustrates in perspective a store-front embodying my new design.

I claim:

The ornamental design for a store-front substantially as shown.

JACOB B. BERLAND.
